(57) **CLAIM**

We claim the ornamental design for a rotating machine for vehicle, as shown and described.

DESCRIPTION

FIG. 1 is a front view of an embodiment of the claimed design;

FIG. 2 is a rear perspective view of the claimed design of FIG. 1;

FIG. 3 is a plan view of the claimed design of FIG. 1; FIG. 4 is a bottom plan view of the claimed design of FIG. 1; FIG. 5 is a right side view of the claimed design of FIG. 1; and, FIG. 6 is a left side view of the claimed design of FIG. 1.

The ornamental design which is claimed is shown in the drawings. The broken lines in the drawings are for illustrative purposes only and form no part of the claimed design.
